UNITED STATES PATENT OFFICE.

ROBERT L. DARTER, OF MURPHYSBORO, ILLINOIS.

STEAM-FAN.

No. 894,941.

Specification of Letters Patent. Patented Aug. 4, 1908.

Application filed October 24, 1907. Serial No. 398,976.

To all whom it may concern:

Be it known that I, ROBERT L. DARTER, a citizen of the United States, residing at Murphysboro, in the county of Jackson and State 5 of Illinois, have invented a new and useful Improvement in a Steam-Fan, of which the following is a specification.

This invention relates to a novel construction of fan adapted to be driven by belting 10 from any engine and especially adapted for use in shops, factories and other places where steam power is available and fans are desired. It is of course obvious, however, that a fan constructed in accordance with my 15 invention may be driven by any suitable means other than steam power.

The invention consists in a depending stationary shaft, a disk carried by said shaft, a revolving casing, and fans carried by said 20 casing and rotated independent of rotation of the casing by frictional contact between rollers carried by the fan shafts, and the disk of the fixed shaft.

In the drawings I have shown a sectional 25 view of my invention in which A represents a ceiling socket in which is rotatably held a cylindrical casing B flanged at its upper end and held in place in the socket by a collar C. Anti-friction balls B' are arranged between 30 the flange of the casing and the collar.

A pulley D is fixed upon the casing and projecting outwardly from the casing and below the pulley, are fan sockets E, in which are held fan blades F. The lower end of the 35 casing is flared outwardly forming an opened conical frame B². In this portion of the casing are journaled downwardly inclined shafts

G which at their lower and outer end carry fan blades H, and at their inner ends are provided with friction rollers K. A fixed shaft I extends through the casing B and within the conical portion of the casing carries a beveled disk J engaged by the rollers K. When the pulley D is driven by a suitable belt or in any other manner, the casing B is 45 rotated about the shaft I, imparting rotation to the fan blades F. The blades H are also carried about the shaft I with rotation of the casing B and are at the same time rotated upon their own axis by engagement of 50 the roller K with the disk J.

What I claim is:—

1. A device of the kind described comprising a ceiling socket, a rotatable casing carried by and depending from said socket, the lower 55 end of said casing flaring out and forming an opened cone, a shaft journaled within the casing a disk upon said shaft, said disk being arranged within the cone, fan-shafts journaled in the casing, fan-blades on said shafts, 60 and rollers upon said shafts engaging the disk, as and for the purpose set forth.

2. A device of the kind described comprising a ceiling socket, a depending fixed shaft, a casing rotatable upon the shaft, a disk bevelled and carried by the lower portion of the shaft, shafts journaled in the casing, blades upon said shafts, and frictional rollers upon 65 said shafts, the said rollers engaging the disk of the fixed shaft.

ROBERT L. DARTER.
